UNITED STATES PATENT OFFICE.

ALBERT SCHMIDT, OF FLINT, MICHIGAN, ASSIGNEE TO CHAMPION IGNITION COMPANY,
OF FLINT, MICHIGAN, A CORPORATION OF MICHIGAN.

SPARK-PLUG.

1,219,590.

Specification of Letters Patent. Patented Mar. 20, 1917.

Application filed January 8, 1916. Serial No. 70,906.

To all whom it may concern:

Be it known that I, ALBERT SCHMIDT, a citizen of the Republic of France, residing at Flint, in the county of Genesee and State 5 of Michigan, have invented certain new and useful Improvements in Spark-Plugs, of which the following is a specification, reference being had therein to the accompanying drawings.

10 The invention relates to spark plugs and has for its object the protection of the insulator from fouling.

In the drawings:

Figure 1 is a longitudinal section through 15 the plug; and

Fig. 2 is a similar view showing a modification.

In the use of spark plugs in explosion engines using low-grade fuels great difficulty 20 is experienced in the sooting of the surface of the insulators so as to destroy their dielectric property. The sooting is caused by the imperfect combustion of the gas in contact with the insulator surface, and on account of the high pressure incident to the 25 explosion the gas is forced against all portions of the structure. With the present invention I have overcome this difficulty by placing the insulator in a chamber in communication with the gas space of the explosion 30 chamber but separated therefrom by means barring the passage of the flame. Thus, while the gases are permitted to pass back and forth between the insulator chamber and the explosion chamber the gas in the former is not ignited and therefore will not 35 produce a carbon deposit.

In detail, A is the metallic casing of the 40 plug and B is the insulator seated therein and surrounding the electrode C. D is an extension of the casing A which surrounds an inwardly-projecting portion of the electrode forming a tubular passage therebetween of relatively small area. The surrounding 45 tubular portion of this casing is preferably lined with an insulator E, such as a wrapping of mica to prevent short circuiting, while the outer end F thereof forms the grounded electrode.

50 With the construction as described, when the gases within the explosion chamber are compressed either by the initial compression or by the pressure of explosion they will be forced through the tubular passage surrounding the electrode into the chamber C

surrounding the insulator B. When the pressure is relieved during the exhaust or suction strokes there will be an outward flow of the gases from the chamber G into the explosion chamber. This flow back and forth will free the passage from any fouling of soot or other material which might short circuit the electrodes. When explosion occurs, the gases will be forced inward as before stated, but the absorption of heat 65 through the walls of the tube will lower the temperature sufficiently to prevent the passage of the flame. Consequently the gas within the chamber G is not ignited and cannot foul the surface of the insulator. 70

In Fig. 2 a modified construction is shown, in which the electrode C is surrounded by a series of baffles H extending inward from the wall of the casing A. The space between the electrode and the baffles is slight, but intermediate adjacent baffles is an expanded chamber of considerable volume. Thus the gas passing into and out from the chamber surrounding the insulator is checked in its velocity by the baffles H which further 80 guards against the possibility of passage of flame. The baffles H may be insulated from the casing by interposed insulation I, and a grounded electrode J extends from the casing into proximity to the end of the electrode C. 85

To successfully bar the passage of flame is essential that the length of the gas passage into the insulator inclosing chamber should have a length considerably greater than its 90 diameter. This is secured by the relatively long tube, as shown in Fig. 1, and by the series of baffles, as shown in Fig. 2. Also as above stated the latter construction forms an additional check in the throttling effect of 95 the chambers between the baffles.

What I claim as my invention is:—

1. In a spark plug, the combination of an insulator, a casing surrounding said insulator and forming an inclosing gas chamber 100 with a restricted passage communicating with the explosion chamber, an insulator lining to said restricted passage, and an electrode passing through said insulator and restricted passage.

2. In a spark plug, the combination with an insulator, of a casing surrounding said insulator and contracted therebeyond to form a restricted tube, an insulator lining for said restricted tube, and an electrode passing 110

through said insulator and said tube free from the walls of the latter, the outer end of said tube forming the coöperating electrode.

5 3. In a spark plug, the combination with an insulator and an electrode passing therethrough and projecting therebeyond, of a casing surrounding said insulator and form-

ing a flame-guard, and having a passage through which the projecting electrode extends restricted and insulated to form high-velocity gas currents therethrough upon variations in pressure in the explosion chamber.

In testimony whereof I affix my signature.

ALBERT SCHMIDT.
